UNITED STATES PATENT OFFICE

THOMAS B. JEFFERY, OF CHICAGO, ILLINOIS.

BICYCLE.

SPECIFICATION forming part of Letters Patent No. 352,190, dated November 9, 1886.

Application filed April 17, 1886. Serial No. 199,219. (No model.)

To all whom it may concern:

Be it known that I, THOMAS B. JEFFERY, a citizen of the United States, residing at Chicago, in the county of Cook and State of Illinois, have invented certain new and useful Improvements in Bicycles, which are fully set forth in the following specification, reference being had to the accompanying drawings, wherein—

10 Figure 1 is a side elevation. Fig. 2 is a section through x x , Fig. 1, showing the construction of the crank-wrist bearing. Fig. 3 is a front elevation of the parts forming a joint in the backbone, said parts shown separated. 15 Fig. 4 is a sectional side elevation of the same joint. Fig. 5 is a section through y y , Fig. 4. Fig. 6 is a front elevation of the hub, crank, foot-lever, link, and one branch of the fork, the ball-joints of the link being shown in longitudinal section. Fig. 7 is an enlarged axial section of one of the ball-joints of the link. Fig. 8 is a perspective of a dust-cover employed at the backbone-joint. Fig. 9 is a section through v v , Fig. 4.

25 The purpose of this invention is to enhance the safety and ease of action of bicycles of the style commonly known as the "safety-bicycle," being such as have the pedal not on the crank-wrist, but on a lever which acts upon the 30 crank-wrist, the pedal being always in the rear of the axle, whereby it is made possible to locate the seat farther to the rear of the vertical plane of the axle, and so diminish the danger of throwing the rider forward over the 35 wheel upon encountering an obstacle.

It comprises devices for varying the reach or length of stroke of the pedal, and for varying the position of the pedal with relation to the seat and axle; devices for easing the action of the pedal and its connection with the crank, and for preventing the joints in its connections binding and cramping by reason of accidental bending of any of the parts; devices for diminishing the jar to the seat and rider 45 caused by the rear wheel—the same being liable to be more serious in this class of vehicles on account of the position of the seat being farther to the rear, so that the rear wheel sustains more of the weight than in those having 50 the seat farther forward—and certain other details of construction, which are fully described, and set forth in the claims.

In the drawings, A is the front or driving wheel.

B is the rear wheel.

55

C is one branch of the fork.

D is the backbone, composed of the arch D' and the part D², which includes the rear fork.

E is the axle; E', the crank.

F is a link pivoted to the fork, a clip or clamp, f, forming the connection between the link and the fork and having the pivot of the link.

G is the foot-lever, which is pivoted on the crank-wrist and connected in front to the otherwise free end of the link F, and having at the rear end the pedal H.

L is a dust-cover, which protects the joint between the two parts D' and D² of the backbone. L² is a fastening-clip for said dust-cover.

The crank-wrist E¹⁰ is fastened to the crank E' in the slot e', and is thereby made adjustable toward and from the axle. I prefer to provide the crank-wrist with an adjustable ball-bearing, and such a bearing is illustrated in Fig. 2.

One of the features of my invention consists in making the bearing of the crank-wrist adjustable to any position desired on the foot-lever, and for this purpose I form the clamp G' to slide and be clamped on the foot-lever G, and provide it with the flange G¹⁰, projecting in the vertical plane of the foot-lever, and through said flange I make the screw-threaded aperture g¹⁰, and I make the case G² of the ball-bearing for the crank-wrist with a threaded boss or annular rib, g²⁰, about midway the length of said case, and of greater diameter than any cap or nut or other projecting part 90 between it and one end of the bearing or box, and bounded by a shoulder, g²¹, on the side toward the other end, so that, the box being inserted through the aperture g¹⁰, the boss g²⁰ may be screwed into the same, and its shoulder 95 g²¹ brought up firmly against the side of the flange G¹⁰. I also find it desirable to adjust the position of the pivot of the link F or the fork C, and for that purpose I provide the clamp f, which slides on the fork and may be clamped 100 at any desired point thereon, and upon said clamp I fix the pivot of the link.

The three adjustments described—viz., the crank-wrist on the crank, the crank-wrist bear-

ing on the foot-lever, and the link-pivot on the fork—permit the variation of the pedal movement in several respects. First, the length of the horizontal movement of the pedal is determined almost entirely by the distance of crank-wrist from the axle; second, the "reach" or length of vertical stroke of the pedal is determined by the relative distances of the crank-wrist from the axle and from the pedal.

10 The mean position of the pedal with reference to the vertical plane of the seat will be determined chiefly by the position of the crank-wrist bearing on the foot-lever, and the mean height of the pedal—or mean distance below the seat—will be determined chiefly by the position of the link-pivot on the fork. Each of these several adjustments affects the others somewhat; but by means of them all all desirable variations may be made in the length of

15 stroke and in the mean vertical and mean horizontal position of the pedal.

Since the link F does not swing in the plane of the rotation of the crank-wrist—that is, since its upper pivot is not in the plane of motion of its lower pivot—it is desirable to provide it with ball-joints, and since these joints are liable to wear it is desirable to provide means for closing up the bearings about the ball-pivot of such joints. It has been usual to

20 form the balls for such joints at the extremity of a rigid stud jutting sideward from the link, and to form the sockets in the foot-lever at one end and in the fork or part attached thereto at the other end; but since the wear is in the

25 direction of the length of the link—and any adjustment for lost motion should be in the direction, that is to say, along the line of the loss of motion by wear—and since the various adjustments of the link on the fork and the

30 crank-wrist bearing on the foot-lever change the direction of the link F with reference to the parts to which it is connected, it is obvious that the parts of the joint which are made movable to take up lost motion should be on

35 the link, since, with reference to the link, the direction of wear does not materially vary, rather than on the connected parts, with reference to which the direction of wear does vary with varying adjustments. I therefore

40 form the sockets of the joints in the link, and provide the connected parts—the foot-lever and the clamp f—with sideward-jutting studs G³ and f', respectively, which terminate in the balls G²⁰ and f¹⁰, fitting the socket-bearings F'

45 in the link, and provide the bolts F¹⁰ F²⁰, screwed into the ends of the link and inwardly terminating in concave bearing-surfaces f¹⁰ f²⁰, fitting the balls. These bolts may be adjusted to take up lost motion in the joints, and are

50 preferably provided with the jam-nuts f¹¹ f²¹, to prevent them from working loose.

By reason of the location of the seat K farther to the rear than in vehicles of the class which have the pedal on the crank-wrist the

55 rising and falling of the rear wheel when passing over obstructions tends to jolt the seat and rider more than in those of that class. To

counteract this difficulty, I make the backbone jointed at d, just above the rear wheel, the joint being between the backbone proper—the part D'—and the fork D². This joint is flexible in the vertical plane of the rear wheel, or the vertical plane of the backbone—which is the same—and is provided with a spring, D³, tending to resist forward flexure. In detail, I prefer the structure shown, viz: The backbone D' terminates in a cross bar or head, D¹⁰, and the fork D² terminates above in a cylindrical box, D²⁰, having a cylindrical transverse socket, d²⁰, having the closed ends d²² 80 and open at the upper side at d²¹ to admit the cross-head D¹⁰. The ends of the cross-head D¹⁰ have the conical cavities d¹⁰, and through the ends d²² of the cylindrical box D²⁰ are screwed the taper-pointed pivots d³ d', whose tapered 85 points enter the conical cavities d¹⁰, and thus form the bearings of the joint d. From the backbone D', just above or forward of the joint d, protrudes the arm or finger D¹¹, which hangs over or behind the upper end of the fork D², and between its overhanging end and the said fork there is interposed the spring D³, acting, as described, to prevent or resist flexure of the joint forward. The rising and falling of the rear wheel will tend to cause flexure 95 of the joint, and thereby the seat will be relieved of the jolting to a large extent.

In order to protect the joint d from dust, I provide the semi-cylindrical cover L, adapted to fit over the cylindrical box D²⁰, and having the slot L' extending from one end to the middle of the length at the middle of the semi-circumference, said slot being just large enough to admit the neck D¹¹ of the cross-head D¹⁰. The edges of the slot L' are folded up to form hooks l', and after the cap L is passed over the box D²⁰, receiving the neck D¹¹ in its slot L', the cap or clasp L², having its edges l² l' hooked to correspond with the hooked edges l' of the cover L, and hollowed at the end l' to fit the neck D¹¹, is slipped on over the joint d, its hooks l' l' being engaged with the hooks l' l', and thereby retained in place.

To protect the crank-wrist bearing from dust, I provide the caps G⁴ and G¹⁰, which are screwed onto the ends of the case G² and have openings g⁴ and g¹⁰ for the wrist or spindle E¹⁰ to pass through. The wrist has a shoulder or flange, e¹⁰, near the crank, which is stopped outside the cap G⁴, and the taper bearing E¹¹ at the other end has the flange e¹¹ stopped inside the cap G¹⁰, while the set-nut E¹² on the end of the wrist E¹⁰ has the flange e¹², which covers the opening g¹⁰ in the cap G⁴ on the outside, and thereby dust is excluded from the bearing, except so much as may enter between the surfaces of the flanges and caps which are in working contact, and substantially dust-tight.

I claim—

1. In combination, the axle-crank, the foot-lever, the swinging link, and the fork, the foot-lever being pivoted on the crank-wrist, the link connected to the foot-lever in front of the

crank-wrist and to a pivot which is vertically adjustable on the fork, substantially as set forth.

2. In combination, the axle-crank, foot-lever, link, and fork, the link being pivoted to the fork and to the forward end of the foot-lever, said foot-lever being pivoted on the crank-wrist, the bearing of said wrist being adjustable at will intermediate the ends of the foot-lever, substantially as set forth.

3. In combination, the axle-crank, foot-lever, link, and fork, the link being pivoted to the fork and to the forward end of the foot-lever, the foot-lever being pivoted on the crank-wrist concave upward in front of and downward in the rear of said pivot, and the length of the crank being adjustable at will, substantially as set forth.

4. In combination, the axle-crank, the foot-lever, the swinging link, and the fork, the foot-lever being pivoted on the crank-wrist, the bearing of the wrist being adjustable on the lever, and the link being connected to the forward end of the lever and to a pivot adjustable on the fork, substantially as set forth.

5. In combination, the axle-crank, the foot-lever pivoted on the crank-wrist, the bearing of the wrist being adjustable on the lever and the wrist being adjustable on the crank, and the link connected to the forward end of the foot-lever and to a pivot on the fork, substantially as set forth.

6. In combination, the axle-crank having the crank-wrist adjustable toward and from the axle, the foot-lever pivoted on the crank-wrist, and the link connecting the forward end of the foot-lever to a pivot adjustable on the fork, substantially as set forth.

7. In combination, the axle-crank having the crank-wrist adjustable toward and from the axle, the foot-lever pivoted on the crank-wrist, the bearing of the wrist being adjustable on the lever, and the link connecting the forward end of the lever to a pivot adjustable on the fork, substantially as set forth.

8. In combination with the crank, the foot-lever pivoted on the crank-wrist, and having at the forward end a lateral stud or wrist terminating in a ball, the fork having secured to it a similar stud, and the link having the spherical sockets or bearings for the balls, substantially as set forth.

9. In combination with the axle-crank, the foot-lever pivoted on the wrist, the link connected to the forward end of the lever and to a pivot on the fork, said connection being by ball-and-socket joints, of which the socket is in the link, and the bearing in said socket adjustable, to take up lost motion, in the direction of the length of the link, substantially as set forth.

10. In combination with the axle-crank and the link swinging from a pivot on the fork, the foot-lever pivoted at the forward end to

the link and intermediate its ends to the 65 crank-wrist, and having the pedal on the rear end, said foot-lever being curved concave upward between the pedal and the crank-wrist and convex upward between the crank-wrist and the link, substantially as set forth.

70

11. In combination with the axle-crank and the link swinging from a pivot on the fork, the foot-lever pivoted to the free end of the link and to the crank-wrist, and bent concave upward in front of and downward in rear 75 of said pivot and formed oval in cross-section, the shorter diameter being horizontal, substantially as set forth.

12. In combination with the axle-crank and foot-lever, the clamp G', secured to the foot-lever, having the transverse threaded aperture g¹⁰, and the journal-box for the crank-wrist exteriorly screw-threaded, and provided with a clamp-shoulder and screwed into said aperture in the clamp G', substantially as set 85 forth.

13. In combination with the case G², having the threaded end, the wrist E¹⁰, having the flange e¹⁰, and the cap G⁴, screwed to the end of the case, and apertured to admit the wrist 90 and abutting against the flange e¹⁰, substantially as set forth.

14. In combination with the case G², having threaded end, the adjustable taper bearing E¹¹, having the flange e¹¹, the cap G¹⁰, screwed 95 onto the end of the case, apertured for the wrist and abutting against the flange e¹¹, substantially as set forth.

15. In combination with the backbone terminating at the rear in a cross-bar, forming 100 lateral gudgeons, the rear fork terminating above in a transverse cylindrical socket fitting the cross-bar of the backbone, suitable center-pins to retain the cross-bar in the socket, and yielding stop to limit the flexure of the 105 joint so constituted, substantially as set forth.

16. In combination with the backbone terminating in the cylindrical cross-bar centrally countersunk at the ends, and having above the cross-bar the overhanging stop D¹¹, 110 the rear fork terminating in the cylindrical cup to receive the cylindrical cross-bar, and provided with the taper-pointed pivots d³ d³, screwed through its ends into the taper sunk ends of the cross-bar, and the spring D³, 115 interposed between the fork and the overhanging stop D¹¹, substantially as set forth.

17. In combination with the backbone joint formed by the cross-head D¹⁰ in the socket d²⁰, the dust-cover comprising the semi-cylinder L, 120 having the longitudinal slot L', with its edges folded over outward to form the hooks l' l', and the clasp L², having the edges folded to engage the hooks, substantially as set forth.
